UNITED STATES PATENT OFFICE.

ALBERT H. TINNERMAN, OF CLEVELAND, OHIO.

CONVERTIBLE GAS-BURNING OVEN.

1,325,767.

Specification of Letters Patent. Patented Dec. 23, 1919.

Application filed February 20, 1915. Serial No. 9,553.

To all whom it may concern:

Be it known that I, ALBERT HENRY TINNERMAN, a citizen of the United States of America, residing at Cleveland, in the county of Cuyahoga and State of Ohio, have invented certain new and useful Improvements in Convertible Gas-Burning Ovens, of which the following is a specification.

My invention relates to improvements in convertible gas burning ovens; meaning thereby the oven of a combined gas and coal range which is adapted to be heated either with gas or solid fuel.

In ranges of this character it has previously been proposed to insert a removable burner member within the oven and provide a forwardly positioned gas and air connection therefor, as through the oven door, while a vent to the chimney stack is adapted to be operated upon the insertion of the burner member for permitting the escape of the products of combustion. However, the forwardly positioned connection for the burner, not only is in the way, but may require special construction of the oven door, while the separation of the chimney vent and the gas and air connection at relatively distant points of the oven, fails to lend itself to convenient and concurrent actuation of the closures therefor. In my improved construction these openings preferably are positioned more nearly adjacent to each other for permitting automatic operation of their respective closure parts.

Preferably, the air-duct for the oven burner is centrally positioned at the rear of the oven and range, and a diagonally positioned box, cutting one corner only of the lower connection of the chimney stack, serves to supply ample volumes of air to the oven burner, without appreciably obstructing the draft of the range. The closures for the air-duct and for the oven vent to the chimney stack are advantageously provided in one sliding member, upon the rear oven wall, which member is equipped with actuating means adapted to be engaged by the oven burner device, whereby said member is automatically opened and closed.

Further explanation of the details of construction embodying my said invention may best be made in connection with the accompanying drawings, wherein:

Figure 1 is a longitudinal sectional view

of a combined gas and coal range, showing it in condition for heating with solid fuel, and the air duct and oven vent closed.

Fig. 2 is a similar view illustrating the same range with the oven burner device inserted in the oven.

Fig. 3 is a transverse sectional view of the range.

Fig. 4 is an enlarged fragmentary view illustrating the position of the exterior connection for the air duct.

Fig. 5 is a fragmentary section illustrating the gas-coupling members.

Fig. 6 is an isometric view of the oven gas-burner device in inverted position.

Fig. 7 is an enlarged fragment, showing a top view of the sliding member and rear oven wall, and

Fig. 8 is an enlarged vertical section of the same parts, better illustrating the actuating means.

Throughout the several figures of the drawings, I have employed the same character of reference to indicate similar parts.

Fig. 1 well illustrates the features of a combined gas and solid fuel range, as it would appear in a longitudinal, vertical section. On the left there is shown the fire box *a* for the solid fuel, while the top, side, and bottom flues, *b*, *c*, *d*, inclose the centrally positioned oven *e*. The bottom flue *b* connects with the chimney stack *f* by means of the flue opening *d'*. Independent gas burners *g* positioned in upper right hand compartments serve to heat one or more cooking holes of the range. All of these features are independent of the invention herein claimed, which pertains solely to the convertible oven.

This oven *e* has a continuous sheet steel bottom *d''*, through which the heat from the solid fuel is adapted to radiate when in use as an ordinary cooking range. The convertible features of the oven will be better appreciated by making reference first to Figs. 2 and 3, which show the oven in condition for heating with gaseous fuel. Diagonally positioned upon the rear wall of said oven is a slide *h* movable within guides or ways *h' h'* permanently bolted thereto. The upper portion of the slide is adapted ordinarily to cover the perforated vent *e'* connecting with the chimney stack, from which the products of gaseous combustion may

be withdrawn from the oven. The lower portion of the slide, in turn, is adapted ordinarily to close the air duct e'' , through which oxygen may be supplied to the oven 5 burner, and a convertible gas connection may be established. The slide h has lateral arms h'' provided with inclined lower faces, and these are adapted to be engaged by the oven burner member of Fig. 6, when the 10 same is inserted in the lower lateral slides provided in the oven. These inclined faces riding upon the rear edge of the burner device, serve automatically to elevate and retain the slide h , as shown in Figs. 2 and 3. 15 Conversely, the said slide will be automatically closed upon the removal of the oven burner device and thereby adapt the oven for heating with solid fuel; the ultimate result being the opening and closing 20 respectively of the oven vent e' and the rear air duct e'' . Moreover, this slide h may be manually opened and closed by means of the pivoted lever i , having a knob or handle i' at its forward end and a connecting link i'' at its rear end. The slide 25 h is provided with a wedging section h^3 , and the ways h' with the wedging section h^4 , as best shown in Fig. 8, whereby said slide will be caused to closely engage or hug the 30 rear wall of the oven and tightly close the perforations or apertures during the period the slide is in its lower-most position.

Fig. 4 illustrates the rear wall of the range and oven with its perforations e'' , 35 which are guarded by a diagonally extending air-duct j , entering one corner of the casing j' , which connects the bottom flue opening d' with the chimney stack f . This duct, however, obstructs said casing but very 40 little, by reason of its shape and position. The main gas connection and air mixer j'' are connected just to the left of this air-duct j .

An excellent idea of the oven burner member may be gathered by referring to Fig. 6, 45 which shows this composite device in an inverted position. Said device comprises a slide or support k , cut away at its sides k' and forming in effect, the bottom for the 50 gas-burning oven. Depending from this slide is a goose-neck gas burner l , which is movably hung to have lateral play, by lugs l' , from the slide k , so that its flaring orifice l'' may accommodate itself somewhat, and 55 make ready connection with the inlet pipe l^3 of the air mixer, (see Fig. 5). An asbestos lined and perforated plate or shield m is spaced apart from the burner and slide k , by the standards m' , so that said plate will 60 normally lie a short distance above the oven bottom d'' , when the gas burner device is inserted within the oven. The perforations m'' , accordingly, serve to admit the air for combustion, directly to the perforated 65 burner l , said air freely entering through

the duct j and opening e'' into the bottom of the oven when the composite burner structure is in position for use. The asbestos lined shield m , however, serves to protect the oven bottom from any excessive heat, while 70 the products of combustion are rapidly withdrawn from the oven through the vent e' and into the chimney stack.

From the foregoing description, it will be understood that the slide h is retained in its elevated position by means of the lateral arms h'' , which bear upon the rear of the plate k of the composite burner structure, as long as the latter is in position within the oven. Upon the removal of said burner 80 structure, however, the said slide is at once released and drops to its lower position; thereby tightly closing the vent to the chimney stack and the air-duct, so that the oven automatically is restored to its condition of 85 use with solid fuel, as above indicated and shown in Fig. 1. The slide may also be manually opened and closed by means of the connecting lever, for the purpose of cleaning or inspection. The gas burner l , provided as it is with a non-rigid top connection, is quite largely self-adapting by reason of the play or movement thereof, so that any warping or expansion of the parts, will not affect the ready establishment of the gas and air 95 connection for the burner, automatically upon the insertion of the composite gas burner member within the oven. The gas supply pipe n at the side of the range, is provided with a controlling valve n' for the 100 oven burner, with which pipe the gas and air mixer j'' is connected at the back of the range. Some minor features of the improvement may be referred to as optional additions to the structure disclosed. Frequently it is found that the draft to the chimney stack is excessive, and in order to regulate the same, I have equipped the slide h with a depending member o , having an 105 opening o' adapted to register with the left hand perforation of the oven vent e' . By means of a rotatable slide o'' , this opening o' may be closed and thereby reduce the draft approximately one-third, if occasion requires. In order to permit the air mixer 110 to enter the oven sufficiently for insuring ready connection with the flaring end of the gas burner l , there is provided upon the lower portion of the slide h , a flaring boss p , which reaches to the oven bottom and accommodates the inwardly extending end of 115 the pipe from the air mixer. This permits the exclusion of practically all the air, both from the air duct and the air mixer, while retaining the simplified automatic means for 120 controlling the same simultaneously with the control of the vent to the chimney stack. In its closed position, the slide h effectively converts the oven for burning solid fuel, while 125 the bottom or floor of the oven is free to be 130

heated throughout its entire area from the bottom flue.

Having now described the preferred embodiment of my invention, I claim as new and desire to secure by Letters Patent, the following:—

1. The combination with a solid fuel range and its oven, of a converting gas-burning member adapted to be inserted and removed from said oven, an apertured air-distributing plate for said member positioned above the oven bottom, a gas and air mixer connection extending to the oven; said oven being provided with an air duct positioned above its bottom, and with a vent to the chimney stack, closure means for each, and means controllable by the movement of the gas-burning member for automatically actuating the said closure means, substantially as set forth.

2. The combination with a solid fuel range and its oven, having an air duct and a gas and air connection extending through one of the vertical oven walls, and a vent from the oven to the chimney stack adjacent thereto, of a converting gas-burning member adapted to be removably inserted in the oven to make gas and air connection, and automatic means for closing the vent and air duct actuated by the movement of said gas-burning member, substantially as set forth.

3. The combination with a solid fuel range and its oven, having an air duct and a gas and air mixer extending through the rear wall of the oven, and a vent therein to the chimney stack, of a slide adapted normally to close said vent and duct openings, a composite gas-burning member adapted to be inserted in the oven and make connection with the gas and air mixer, and automatic means governed by the movement of said member for actuating the slide, substantially as set forth.

4. The combination with a solid fuel range and its oven; the latter being provided with a vent to the chimney stack in its rear wall, an air duct and a gas and air mixer connection extending through its rear wall, said oven having an unobstructed bottom or floor above the bottom flue of the range, of a converting gas-burning member adapted to be removably inserted in the oven, and closure means for controlling the vent and air duct in said oven wall, substantially as set forth.

5. The combination with a solid fuel range and its oven; the latter being provided with a vent to the chimney stack in its rear wall, an air duct and a gas and air mixer connection extending through its rear wall, said oven having an unobstructed bottom or floor above the bottom flue of the range, of a converting gas-burner member adapted to be removably inserted in the oven, an apertured air-distributing plate for said member positioned above the oven bottom,

and means automatically controlled by the movement of said gas-burner member for opening and closing the vent and air duct, substantially as set forth.

6. The combination with a gas-burning range and its oven; said oven having an air duct in its rear wall adjacent to the lower portion of the chimney stack connection, of an independent casing connecting said duct with the external air, a gas and air mixer connection extending to the oven, means for opening and closing said air duct and gas and air mixer connection, and a converting burner device adapted removably to be inserted in the oven, substantially as set forth.

7. The combination with a solid fuel range and its oven; the latter being provided with a plurality of vents to the chimney stack, of a slide within the oven adapted to control said vents, an adjustable member associated with the slide individually adapted to control one of said vents, a converting gas burner member adapted to be removably inserted in the oven, and means automatically controlled thereby for operating said slide, substantially as set forth.

8. The combination with a solid fuel range and its oven, of a gas and air mixer connection extending within the oven through a lateral air-duct, a slide also within said oven having a boss adapted removably to fit over said gas and air mixer and the air-duct, a removable gas-burner adapted to be inserted in the oven, and means for operating the slide, substantially as set forth.

9. The combination with a solid fuel range and its oven; said oven having an air-duct in its rear wall adjacent to the lower portion of the chimney stack connection of the solid fuel range, of a separate casing extending within said chimney stack connection and connecting the air-duct with the external air, a gas and air mixer connection extending to the oven, means for removably closing said air-duct and gas and air mixer connection, and a converting gas-burner device adapted removable to be inserted within the oven, substantially as set forth.

10. The combination with a gas heated oven, of a gas and air mixer connection extending to the oven, and a converting burner device adapted to be removably inserted within the oven, an apertured air-distributing plate for the burner, comprising a slide and a loosely supported burner-member thereon, equipped with a flaring orifice adapted to fit the gas and air connection, substantially as set forth.

11. The combination with a solid fuel range and its oven; the latter being provided with a vent to the chimney stack and positioned above the bottom flue of the range to be normally heated thereby, of an air-duct and a gas and air mixer connec-

tion extending through the rear wall of the oven, whereby the oven bottom is left unobstructed, a converting gas-burner member adapted to be removably inserted within the oven, a slide controlling said vent to the chimney stack and the air-duct, and means operated by the movement of the gas-burner member for actuating said slide automatically to open or close the vent and air-duct at the same time, substantially as set forth.

12. The combination with a gas-heated oven, of a gas and air mixer entering through a vertical wall, a converting burner device adapted to be removably inserted to make connection therewith, a slide; said slide being mounted upon the side wall in question in position alternatively to cover the gas and air mixer and an opening in said vertical wall connecting with the chimney stack or to uncover the same simultaneously, and operating means associating the slide and the burner member, substantially as set forth.

13. The combination with a gas-burning range and its oven; said oven having an air duct in one of its vertical walls adjacent to the lower portion of the chimney stack connection, of a lateral casing connecting said duct with the external air and partially entering within the lower portion of

said chimney stack connection, substantially as set forth.

14. In a range of the class described, the combination with its oven, of a fixture comprising a gas and air mixer connection extending to the oven through its rear wall, and a converting burner device adapted for removable insertion within the oven, comprising a sliding support and a loosely mounted burner-member thereon equipped with a goose-neck and flaring orifice adapted to conform to and fit the gas and air fixture, substantially as set forth.

15. In a range of the class described, the combination with its oven having a vent to the chimney stack connection and an air duct positioned in one of its vertical walls, of a slide adapted simultaneously to cover and uncover said vent and duct, wedging means for effecting a relatively tight closure thereby, a converting gas burner member, and means associated with said member and slide automatically actuating the latter through the movement of the burner member, substantially as set forth.

In testimony whereof I do now affix my signature in the presence of two witnesses.
